CLAIM

The ornamental design for a portion of a table top, as shown and described.

DESCRIPTION

FIG. 1 is an upper perspective view of a portion of a table top in accordance with a preferred embodiment of the present invention;

FIG. 2 is a lower perspective view of a table top illustrating a preferred embodiment of the invention;

FIG. 3 is a bottom plan view of the table top shown in FIG. 2;

FIG. 4 is a lower perspective view of a table top illustrating another preferred embodiment of the invention; and, FIG. 5 is a bottom plan view of the table top shown in FIG. 4.

The broken lines shown in the figures are for illustrative purposes only and form no part of the claimed design.
